United States Patent Office

Des. 191,054
Patented Aug. 8, 1961

191,054

ROUNDABOUT

Carl L. Hannas, St. Paul, Alberta, Canada

Filed Mar. 7, 1960, Ser. No. 59,647

Term of patent 7 years

(Cl. D34—5)

FIG. 2.

FIG. 3.

FIGURE 1 is a top plan view of a roundabout showing my new design;

FIGURE 2 is a side elevational view; and

FIGURE 3 is a perspective view from above of the roundabout.

I claim:

The ornamental design for a roundabout, as shown.
